UNITED STATES PATENT OFFICE.

ONNIG ENSANIAN, OF GREEN ISLAND, NEW YORK.

SHOEMAKER'S SEWING-MACHINE.

1,218,637.

Specification of Letters Patent. Patented Mar. 13, 1917.

Application filed May 19, 1914. Serial No. 839,635.

To all whom it may concern:

Be it known that I, ONNIG ENSANIAN, a subject of the Sultan of Turkey, residing at Green Island, in the county of Troy, State 5 of New York, have invented certain new and useful Improvements in Shoemakers' Sewing-Machines, of which the following is a description, reference being had to the accompanying drawings, forming a part 10 hereof.

My invention relates to boot and shoe making machinery and has for its object to provide a machine for shoemakers' use which will permit of the entire work of machine sewing, trimming, sand papering and 15 polishing necessary in making or repairing boots or shoes to be completed without requiring the shoemaker to leave his seat.

With these and other objects hereinafter 20 explained in view, my invention consists in the construction and combination of elements hereinafter described and claimed.

Referring to the drawings:

Figure 1 is a front view of a shoe sewing 25 machine having my invention embodied therein.

Fig. 2 is a top plan view of the machine shown in Fig. 1, with the sewing mechanism removed; and

Fig. 3 is a vertical cross sectional view on line *b*—*b* of Fig. 2.

In the drawings, 1 indicates the head of a shoe sewing machine of ordinary construction, in which the main shaft 2 is provided 35 with the usual pulley 3 and hand wheel 4. This sewing machine head is mounted on a raised portion 5 of a table top 6 which is supported at opposite ends by legs 7 and 8 which are suitably connected by brace 9.

The main portion of the table top 6 is arranged at a comparatively low level, so as to be easily reached by a shoemaker sitting before it in a chair of usual height. This low portion of the table top is preferably 45 made of greater breadth than in the usual machine so as to afford plenty of space for implements, nails, pegs and anything else needed in the making or repairing of boots and shoes.

On the leg 7 is supported a stub shaft 10 on which is mounted a fly wheel 11 provided with a crank pin 12 from which a pitman 13 leads to a treadle 14 mounted to rock on rod 15, the construction being that of the

ordinary shoemaker's sewing machine. The 55 fly wheel 11 is grooved, as shown, and a belt 16 leads from the fly wheel to pulley 3.

The legs 7 and 8 are provided with forwardly extending brackets 17 and 18 provided with bearings arranged a little below 60 the level of the lower part of the table top 6 in which bearings is supported a shaft 20 which carries the rotary tools such as are usually made use of in trimming and finishing a boot or shoe after the sole and heel 65 are sewed or pegged to the upper, such for instance as a cutting trimmer 21, sand paper wheels 22 and 23 and buffing wheel 24.

The shaft 20 is arranged to be driven in any convenient way from the fly wheel 11. 70 In the construction shown, the fly wheel is provided with a pulley 25 and shaft 20 is provided with pulley 26, the pulleys 25 and 26 being connected by belt 27.

The sewing machine is also preferably 75 provided with a thread twisting device arranged to be driven from the main shaft of the sewing machine head through the hand wheel 4. This thread twisting device comprises a hollow shaft 30 mounted in a 80 bracket 31 secured to the sewing machine head having on one end a disk 32 which carries a series of pins on which thread spools 33 are mounted. The hollow shaft 30 is provided with a friction wheel 34 85 which is adapted to be driven by the hand wheel 4. In use, the threads from the spools 33 are threaded through the hollow shaft and are drawn out together by hand as wanted, being twisted together as they are 90 drawn out by the rotation of the shaft 30.

Having thus described my invention, what I claim is:

1. In a machine adapted for sewing, trimming, polishing and finishing work, a table 95 mounted on a stand having end supports, a sewing head carrying a belt wheel mounted on said table, a shaft carrying a belt wheel rotatably mounted in said supports and extending beyond the end of one thereof, a 100 trimming wheel mounted upon said extended end, polishing and finishing wheels mounted upon said shaft intermediate of the end supports, a double belt wheel mounted on one end support, a belt running 105 from one belt wheel thereof over the belt wheel carried by the sewing head, a belt running from the other belt wheel over the

belt wheel upon said shaft, a foot treadle, and a connection therefrom to actuate said double belt wheel.

2. In a shoe sewing machine, a sewing head, a driving shaft therefor provided with a hand wheel, a pulley upon said shaft, a fly wheel comprising two grooved pulleys, a treadle for operating said fly wheel, a connection from one of said grooved pulleys 10 to said sewing head shaft, a shaft carrying finishing and trimming wheels, a connection from the other of said pulleys to drive the

shaft of the trimming and finishing wheels, and a thread twisting mechanism mounted upon the sewing machine frame and provided with a grooved pulley engaging the hand wheel of the sewing mechanism. 15

This specification signed and witnessed this 13th day of May A. D. 1914.

ONNIG ENSANIAN.

In the presence of—

MANOUG MUGUERDITCHIAN,
Wm. F. Doyle.
